BRIDGE ELEMENT

Filed May 19, 1928

Inventor
Paul Ebeling
By his Attorney
George C. Henrion

UNITED STATES PATENT OFFICE

PAUL EBELING, OF NEW YORK, N. Y.

BRIDGE ELEMENT

Application filed May 19, 1928. Serial No. 279,080.

This invention relates to improvements in bridges, particularly bridges to be used at street crossing, etc., as for instance described in my co-pending application Serial No. 121,5391, filed July 9, 1926.

It is the principal object of this invention to provide a foldable or collapsible bridge which may be readily set up, for instance against the wall of a house and allow pedestrians, etc., to safely cross a street intersection by stepping from the house onto the bridge and then into the house on the opposite side of the street. It will be clear that in this manner the bridge may also be readily used 15 as a fire escape, etc.

It will be clear that any number of such bridges or bridge elements may be used to constitute a bridge for the crossing of comparatively wide streets, by simply placing the end 20 part of one element against the end parts of the other end by simply setting the bridges end to end.

Another object of my invention is the provision of a bridge element having a roadway, 25 which, while strongly constructed, is adapted to carry a great number of pedestrians and other loads, and which may be readily folded or wound upon or from suitable rollers or other means in order to avoid obstruction of 30 the view when the bridge is not in use, as for instance not to prevent the free view from the windows of a house against which the bridge element is placed.

A further object of my invention is the provision of a bridge element, allowing a ready 35 folding of the bridge proper against its support which may either be effected by manual labor, by means of counterweights, etc., or by motoric force.

40 A still further object of my invention is the provision of a bridge element equipped with a counter-weight frame or the like to facilitate the folding of the roadway against the supporting parts.

45 It is also one of the objects of my invention to construct the mechanism for effecting the folding and unfolding of the roadway so that it can readily be operated and is so combined with the bridge as to be readily accessible; and to construct the foldable roadway so

that it may be folded into a suitable chamber provided in the roadway below the street level, or to construct this roadway in a plurality of parts.

It will be understood that the roadway of 55 the bridge element may be set up at an inclination so as to give ready access, or that suitable stairs may be provided by means of which pedestrians can readily enter upon the roadway.

50 Lamps, advertising signs, flags, and other paraphernalia may be conveniently combined with any of the bridge elements of my invention, and these elements may be constructed with or without foot parts according to requirement or the special purpose for which 55 they are to be used.

The balusters used in combination with my bridge element are foldable against the girders supporting the roadway, and these and 70 other objects and advantages of my invention will become more fully known as the description thereof proceeds, and will then be specifically defined in the appended claims.

75 In the accompanying drawings, forming a material part of this disclosure:

Fig. 1 is a side-elevation of a bridge element constructed according to my invention.

Fig. 2 is a top plan view thereof seen in the direction of line 2-2 of Figure 1.

80 As illustrated each bridge element has a pair of vertical posts 10 adapted to be placed with their base 11 against a house wall etc., and secured at their lower ends in said base-plate or foot 11 against which they are braced 85 by brackets 12, or the like.

The roadway consists of a plurality of horizontal, parallel and spaced side girders 13 pivotally attached at one end to suitable brackets 14 on the vertical posts 10, and supported by a frame 15. Cables 16 are secured at their lower ends to the outer end of frame 15, and are guided through suitable openings in a cross-bar 17 secured between the posts 10 and carry counterweights 18. To facilitate the 90 elevation of the bridge a counter-balance bracket 19, carrying a suitable weight 20, connected therewith by means of bars 22 is provided which is braced near its lower ends 95 by means of braces 21 against the girders 13. 100

The elevation of the bridge girders against the posts 10 is effected by means of cables 23 secured at their outer ends to the L shaped front cross-bar 24 and guided over rollers 25 on a cross-bar 26 connecting the posts 10 near the upper end thereof. The cables are then guided along posts 10 downward, and around drums 27 to which their ends are secured, and which can be operated by means of the customary crank handles 28. Or, the elevating of the girders and the bridge bed therein may also be effected if desired by hand, by means of chains 29 or the like secured at one end to the side faces of the girders, as at 30, and guided through suitable sleeves 31 or the like, movably attached to cross bars 32 secured to the posts 10 so as to project beyond the same, and to the rear ends of said bars 32 substantially vertical braces 33 for the posts are attached, the lower ends of which are anchored in the foot parts 11.

The roadway proper or walk for the pedestrians etc., consists of a plurality of interconnected parallel cross-slats 34, adapted to be rolled upon or from a roller 35 extending on one side beyond post 10 and carrying a suitable operating crank handle 36.

Cables 37 are attached to the front end of the walk, and are then guided over a roller 38 near the outer ends of the girders and over a roller 39 to which their ends are secured, and which is operated by means of a crank 40.

Braces 41 are pivotally connected at their upper ends to the side faces of posts 10, and their lower ends engage pins 42 projecting from the side faces of girders 13 from which they may quickly be detached. Similar braces 43 are also pivoted at their upper ends to the side faces of posts 10 while at their lower ends they are removably attached to pins 44.

Rail posts 45 are pivotally attached at their lower ends to the girders 13 and carry at their upper ends the balusters 46 pivotally secured thereto so as to allow a folding of the balusters against the upper face of the girders.

The frame supporting the side girders is composed of the side bars 15 connected by cross bar 51, and longitudinal bars 47 attached at one end to end bar 24 and at the other end to a cross-bar 48 between posts 10. Lamps 49 on suitable brackets are provided at both outer sides of posts 10, and a sign board 50, adapted to contain any suitable inscription or flags etc. is supported on an upper cross-bar connecting the posts 10.

The operation of my improved collapsible road-crossing bridge elements will be readily understood from the above description by inspection of the drawings, and it will be seen that when necessity arises any number or series of these elements may be combined to bridge a crossing or act as a fire escape etc., without impeding the regular traffic there-

under and without obstructing the view of the traffic officers, drivers, etc.

The bridge can be readily set up or removed without special effort or the necessity of using special machinery or skilled labor, and may be placed at any suitable angle to the street and to other bridge elements, so that pedestrians can easily climb the roadway and pass the street crossings in safety, or if the footless element is set up against houses on opposite sides of a street, the persons may pass from the windows onto the bridge and into the windows of the opposite house.

When not in use the bridge element can quickly be collapsed so as not to obstruct the view, and in case of fire a safe passage from a burning building to a place of safety in a building on the opposite side of the street may be provided.

It will be understood that I have disclosed the preferred form of my invention as an example only of the many ways to practically construct the same, and that I may make such changes in the general arrangement and in the construction of the minor details thereof as come within the scope of the appended claims without departure from my invention and the principles involved.

Having thus described my invention, what I claim as new, and desire to secure by Letters Patent is,—

1. Bridge elements for forming bridges and fire escapes, each comprising a plurality of posts, a pair of parallel spaced girders hinged at one end to said posts intermediate their length, braces attached to said posts and removably secured to said girders, a frame in which said girders are supported, a weighted counterbalance frame at one end of said girders for holding the same in their horizontally extended position, cables attached to said supporting frame, and weights on the ends of said cables, a means for elevating and lowering said girders against and from said posts, a foldable roadway between said girders, and a means for winding and unwinding said roadway.

2. Bridge elements for forming road crossing bridges, each comprising a pair of posts, foot parts therefor, a pair of spaced parallel girders, means for pivotally connecting the inner ends of said girders with said posts intermediate their length, braces attached to said posts at one end and removably attached to said girders at their other end, a frame bracket on one end of said girders, an elevated weight on said frame to counterbalance the girders, a cable secured at one end to said frame and passed through said posts at an elevation from their parts, weights at the ends of said cables behind said posts, cables attached to the free ends of said girders, rollers on said posts over which said cables are guided, a means for winding and unwinding said cables, braces for said posts, foldable

balusters on said girders, a transverse roller between the posts, a foldable roadway composed of slats adapted to be wound upon said roller and unwound therefrom, and a means for operating said roller.

5 Signed at New York, in the county of New York and State of New York this 16th day of May, A. D. 1928.

PAUL EBELING.
